Inventor:

Mary P. Carpenter

United States Patent Office.

MARY P. CARPENTER, OF SAN FRANCISCO, CALIFORNIA.

Letters Patent No. 99,158, dated January 25, 1870.

IMPROVEMENT IN NEEDLE AND ARM FOR SEWING-MACHINE.

The Schedule referred to in these Letters Patent and making part of the same.

To all whom it may concern:

Be it known that I, MARY P. CARPENTER, of the city and county of San Francisco, State of California, have invented certain new and useful Improvements in Needle-Arms and Needles to Sewing-Machines; and I do hereby declare that the following is a full, clear, and exact description of the same, reference being had to the accompanying drawings, and to the letters marked thereon.

My invention relates to certain improvements in that class of devices that has for its object the facilitating of the operation known as threading the needle of sewing-machines, and consists of certain details of construction of the needle, and the arm or bar to which the needles are attached, as hereinafter described.

To enable others skilled in the art or science to which it most nearly appertains, to make and use my invention, I will proceed to describe fully its construction and operation.

In the drawings—

Figure 1 represents a side elevation of a needle, and a portion of an arm having my improvement.

Figure 2, a rear elevation of same.

Figure 3, a view of under side of same, showing the needle in section.

Figure 4 is a side elevation of such a needle, much enlarged.

Figure 5 is a front elevation of same.

Like letters refer to like parts.

It will be seen, by reference to the figures, that my needle differs from most others, in having a longitudinal slit or passage, *a*, extending from below the eye up through the body, and out at the top, and in having the upper ends *k*, thus formed, flattened, and provided with lugs or projections *b*.

It will also be seen, by reference to figs. 1, 2, and 3, that the arm differs essentially from most other sewing-machine arms, in being divided at its extremity, by means of the longitudinal slot *c*, and the transverse slot *d* and opening *e*, into four parts, forming, by means of the screw *f*, a clamp, *l*.

To place the needle in position, with the passage *a* slightly open at the top, but closed near the eye, as shown in figs. 1, 2, and 3, I first place a small slip of paper, or other substance about equal in thickness to the thread to be used, between the faces of the passage *a*, at the upper end, and grasping the needle between the thumb and fingers of the left hand, in such a manner as to close the passage, insert the needle, so that while the lugs *b* enter the slot *c*, the paper will enter the transverse slot *d*; then, by turning the screw *f*, the needle will be held fast, and the paper can be withdrawn.

From this description, it will be observed that the object of the lugs *b* is to obtain abundant bearing-surface for the faces of the clamp to press against;

but it will also be seen, that the same object would be attained without the lugs, by flattening the upper ends of the needle, as described.

The operation of threading will be readily understood, by supposing the line *g h* (fig. 2) to represent the position of a thread after one end has been passed through the opening *c*, and the line *g' h'*, passing through the eye, the position of the same thread after the operation of threading has been performed, for it is plain, that if we grasp the thread with one hand at *g*, and with the other hand at *h*, we can carry it directly downward into the slot *d* and passage *a*, and down between the yielding faces of the passage *a* to the line *g' h'*, and that when the thread has reached the eye, the passage *a* would again close, and prevent it from escaping.

I am aware that needles have been invented, having a slit or passage from some point above to some point below the eye, through which the thread is admitted; but when both parts of the needle, forming this slit or passage, are not firmly secured at both ends, it is evident that needles so constructed must be made very large in proportion to their strength, and therefore are not fit for fine sewing; and, also, if the slit or passage does not extend up so high that the loose end is never thrust through the cloth, there is a liability to catch in passing.

To obviate this difficulty, a needle has been invented, having two eyes, a large and a small one, connected by a slit or passage; but this two-eyed needle has an element of weakness, in its great length and peculiar construction, equal, perhaps, to some of the others referred to, while, by my invention, all the advantages attained by any of the others are secured, combined with greater simplicity of construction, and a needle is produced that can be used for the finest kind of work, on account of its great strength in proportion to its diameter.

The two-eyed needle being necessarily longer than the ordinary needle, must have an arm, constructed to correspond to that length, while an arm having my improvements may be used with any kind of a needle.

Having thus described my invention,

What I claim, and desire to secure by Letters Patent, is—

The combination, with the needle-arm, provided with the clamp *l*, the opening *e*, and slot *d*, of the needle, having the passage *a*, the flattened ends *k*, and the lugs or projections *b*, the whole constructed and arranged to operate substantially as and for the purpose specified.

In testimony whereof, I have hereunto set my hand and seal.

MARY P. CARPENTER. [L. S.]
